(57) **CLAIM**

The ornamental design for a lathe, as shown and described.

DESCRIPTION

FIG. 1.1 is a front view of a lathe showing my new design;

FIG. 1.2 is a back view thereof;

FIG. 1.3 is a left view thereof;

FIG. 1.4 is a top plan view thereof;

FIG. 1.5 is a sectional view taken along line A-A in FIG. 1.4;

FIG. 1.6 is a front left top perspective view thereof;

FIG. 1.7 is a back left top perspective view thereof.

The parts shown by means of broken lines in the reproductions depict portions of the lathe that form no part of the claimed design.
